UNITED STATES PATENT OFFICE

92,794

DESIGN FOR A POTATO SLICER

Raphael Crocco, Westfield, N. J.

Application April 12, 1934, Serial No. 51,386

Term of patent 7 years

To all whom it may concern:

Be it known that I, RAPHAEL CROCCO, a citizen of Italy, residing at Westfield, in the county of Union and State of New Jersey, have invented a new, original, and ornamental Design for a Potato Slicer, of which the following is a specification, reference being had to the accompanying drawing, forming part thereof.

In the drawing:

The figure is a perspective view of a potato slicer, showing my new design.

I claim:

The ornamental design for a potato slicer, as shown.

RAPHAEL CROCCO.
